US00D621562S

(12) **United States Design Patent**
Marshall

(10) **Patent No.:** US D621,562 S
(45) **Date of Patent:** ** Aug. 10, 2010

(54) **RETRACTABLE LEASH**

(75) Inventor: **David Christopher Marshall**, Aurora, CO (US)

(73) Assignee: **LeashLocket, Ltd.**, Denver, CO (US)

(**) Term: **14 Years**

(21) Appl. No.: **29/355,372**

(22) Filed: **Feb. 5, 2010**

(51) **LOC (9) Cl.** 30-04

(52) **U.S. Cl.** D30/153

(58) **Field of Classification Search** ..... D30/151-155, D30/144, 199, 160; 119/792-798, 850, 855-859, 119/863-865, 654, 905, 907, 815, 712, 802, 119/784, 769, 760; 242/381.1-381.2, 385.4, 242/378.3, 376.1, 385.1, 916, 601, 570, 405, 242/404, 371, 223, 170, 388.1, 405.2, 377, 242/381.3, 381.6, 405.3, 388.6, 384.7, 382, 242/396.1, 404.1, 380, 395; 362/108; 33/767, 33/769, 414, 761; D12/400; D3/229, 230, D3/207, 208; 40/1.5, 455, 640, 303; 206/63.3, 206/459.5, 702, 408; D6/515; D8/358, 360, D8/347, 360.1, 359, 356, DIG. 1, 18, 98, D8/99, 38; D24/145; D10/57, 104, 72; D20/28; 224/666, 678; 16/445; 283/74, 70; D11/232; 24/163 K, 122.3; 428/3, 4; 54/76; 63/29.1; 191/12.2 R, 12.4; D13/154, 153, 137.4, 155; D19/69, 67, 35, 65, 72, 99; 379/438; 446/26; 473/576; D22/140, 126-133; 174/135; 439/504, 439/13, 501; D34/33; 188/83, 82.1, 65.1; 254/134.3 FT; D29/124; D26/37, 38; 43/42.28, 43/42.35, 42.45, 42.39, 42.47, 42.46, 42.48, 43/42.19; 30/321, 155, 294, 317

CLAIM

The ornamental design for a retractable leash, as shown and described.

DESCRIPTION

FIG. 1 is a front perspective view of a retractable leash, showing my new design;

FIG. 2 is a top plan view of the invention illustrated in FIG. 1;

FIG. 3 is a rear elevation view of the invention illustrated in FIG. 1;

FIG. 4 is a bottom plan view of the invention illustrated in FIG. 1;

FIG. 5 is front elevation view of the invention illustrated in FIG. 1;

FIG. 6 is a right elevation view of the invention illustrated in FIG. 1; and,

FIG. 7 is a left elevation view of the invention illustrated in FIG. 1.

Any broken lines and broken line portions shown are not claimed.

1 Claim, 3 Drawing Sheets
